**CENTRALIZED TRAFFIC CONTROL SYSTEMS
FOR RAILROADS**

Nelson B. Coley, Rochester, N. Y., assignor to General Railway Signal Company, Rochester, N. Y.

Application August 3, 1951, Serial No. 240,687

10 Claims. (Cl. 246—3)

This invention relates to centralized traffic control systems for railroads, and it more particularly pertains to a system for checking that a route is set up as designated before the transmission of a signal clearing code for governing entrance to the route is permitted.

Although centralized traffic control systems of the code communication type are so organized in general as to have all safety circuits in the field so that an erroneous code cannot create a dangerous condition, an erroneous code can cause the establishment of a wrong route under certain conditions. If the operator of the control machine should not realize a wrong route had been set up, there could be considerable costly delay in train operation before the error would be corrected.

Generally speaking, and without attempting to define the scope of the present invention, the present invention prevents the setting up of a wrong route by permitting the transmission of a signal clearing code from the control office only after the track switches have been properly positioned in correspondence with the switch control levers for such track switches at the control office for an entire route emanating from the signal desired to be cleared. This is accomplished by the knocking down of a magnetic stick normal or reverse switch indication relay whenever it is designated that the associated track switch is to be operated to its opposite position. The picking up of the magnetic stick relay for the new position that has been selected in response to an indication transmitted from the field station is required in order to close a circuit portion for a code determining relay associated with the transmission of a signal clearing code to permit the transmission of such a code.

Another feature of the system provided by the present invention is that for initiation of the code communication system it is only necessary to actuate the respective switch and signal control levers for designation of the desired new positions, without requiring the actuation of a start button, to initiate the code communication system from its state of rest into operation for the transmission of the new control that has been designated. This starting means is effected by use of polarized circuits for the control of normally energized start relays.

An object of the present invention is therefore to provide an improved system of code communication involving the checking by indications received from the field of the positioning of track switches for a route before the transmission of a signal control governing entrance to the route is permitted.

Another object of the present invention is to provide control office starts directly in response to the actuation of switch and signal control designating means by polarity control of normally energized change relays, without requiring the use of conventional start push buttons or switches.

Other objects, purposes and characteristic features of the present invention will be in part obvious from the accompanying drawings, and in part pointed out as the description of the invention progresses.

In describing the invention in detail, reference is made to the accompanying drawings in which parts having similar features or functions are designated by similar letter reference characters, and in which:

- 5 Fig. 1 illustrates apparatus at the control office for the initiation of the code communication apparatus into different cycles of operation for the transmission of respective switch and signal controls;
- 10 Fig. 2 illustrates a section of the control panel of a control machine at the control office having a track diagram of the track layout for which this embodiment of the present invention is provided;
- 15 Fig. 3 illustrates apparatus at the field station effecting the control of respective track switches and signals of a typical track layout in accordance with control codes received from the control office, and apparatus for the transmission of indications to the control office as to the conditions of the respective track switches at the field station.
- 20 Conventional schematic diagrams have been used for the disclosure of the system organization in the drawings, such drawings being prepared more particularly to facilitate an understanding of the mode of operation of the system, rather than to attempt to point out the detailed construction and specific arrangement of components that may be provided by those skilled in the art in accordance with the requirements of practice. The symbols (+) and (—) have been used to indicate connections to the respective positive and negative terminals of suitable batteries or other sources of direct current, and the symbols (B+) and (B—) have been used to indicate connections to the respective positive and negative terminals of a suitable split battery, or other source of direct current, having a center tap designated as (CN).
- 25 30 35 Although it is to be understood that the present invention is readily adaptable for the communication of switch and signal controls from a control office to a remote field station for a track layout having a relatively large number of track switches and signals to be controlled, for the purpose of simplification of this embodiment of the present invention, it has been considered sufficient for an understanding of the present invention that it be applied to the relatively simple track layout illustrated in Fig. 3, and shown in Fig. 2 as being constructed as 40 a diagram on the panel of the control machine at the control office. This track layout can be considered as a small part of a large track layout of an interlocking plant wherein three parallel tracks are interconnected by crossovers 1TS and 3TS. The track layout is divided into 45 50 detector track sections in the usual manner, and signals 2R, 4R, and 6R are provided for governing eastbound traffic through the track layout while the signals 2L, 4L, and 6L are provided for governing westbound traffic through the track layout. The type of signals employed 55 can be of any conventional type such as searchlight, position light, color light signals having individual color lamp units, or semaphore signals. The operation of the track switches of the respective crossovers 1TS and 3TS is by power switch machines at the respective ends of the 60 crossovers, the switch machines 1ASM and 1BSM being associated with the operation of the track switches at the respective ends of the crossover 1TS, while the switch machines 3ASM and 3BSM are associated with the power operation of the track switches at the respective ends of the crossover 3TS.
- 65 It is to be understood that the system includes a suitable centralized traffic control machine at the control office, such as is well known in the art, for use in governing traffic through the track layout. This machine has 70 a suitable control panel 20 having a diagram of the track layout constructed thereon and having manually operable switch and signal positions designating means SML and

SGL respectively, on the control panel either below the track diagram, or disposed along the track diagram, in accordance with the requirements of practice, as a means by which an operator of the control machine may designate the respective routes to be set up through the track layout. It is to be understood that suitable indicator lamps such as the typical switch correspondence lamps 1CK and 3CK, together with other indicator lamps (not shown), are provided on the control panel for the purpose of keeping the operator informed as to the conditions of the apparatus at the field station. The levers 1SML and 3SML are two position levers provided for the designation of the respective normal and reverse positions of the respective crossovers 1TS and 3TS, and similarly three position signal control levers 2SGL, 4SGL, and 6SGL are provided in accordance with the usual practice for the manual designation of the clear or stop indication desired to be displayed by the associated signals for both directions of traffic.

A normally energized change relay CH is associated with each of the switch and signal control levers SML and SGL as a start relay to be dropped away in response to the movement of its associated lever for initiating the system into a cycle of operation for the communication of the designated switch or signal control. These relays are actuated by reversal of polarity upon the movement of the associated switch or signal control lever to a different position.

Relays LC are provided in association with the respective change relays CH, one relay LC being provided for each change relay CH. The purpose of these relays LC is to determine the code transmitted during any one cycle of operation of the code communication system, and their pickup circuits are so organized that only one of these relays can be picked up at a time. Each relay LC when picked up is maintained energized for the duration of a control cycle of operation of the code communication system by a stick circuit including the winding of a relay LCS which when picked up prevents the energization of another relay LC until the termination of the cycle of operation of the communication system that has been initiated.

Inasmuch as the present invention is applicable to different types of code communication systems known in the art, it is considered unnecessary for an understanding of the present invention to disclose the specific code communication apparatus. The code communication apparatus can be provided, for example, as disclosed in the prior application of Coley and Albrighton, Ser. No. 207,253, filed January 23, 1951, as disclosed in my application, Ser. No. 240,086, filed of even date with the present application, which has resulted in U. S. Patent No. 2,626,314, dated January 20, 1953, or as disclosed in the Hailes et al. patent, No. 2,399,734, dated May 7, 1946. This embodiment of the present invention has been particularly adapted for use with the code communication system as disclosed in my application, Ser. No. 240,086, filed of even date with the present application, which has resulted in U. S. Patent No. 2,626,314, dated January 20, 1953. Thus the relay contacts of relays identified by letter reference characters but with no circuits shown for the windings of the relays are to be considered as contacts of relays bearing similar reference characters in my above mentioned co-pending application, it being considered unnecessary to show the circuits for these relays in this case for an understanding of the present invention. Thus the contacts of relays L, CS, CSP, CP, CPP, C, 1V, 2V, 3V, 4V, and of a code oscillator CT are of relays having their operations and control circuits specifically described in my above mentioned co-pending application.

Relays 1V, 2V, 3V and 4V are stepping relays that are operated successively and are used in setting up the sequence of communication of the respective code characters.

Relay L is a line relay at the control office that is nor-

mally energized by a line circuit (not shown) extending from the control office to the field station as indicated by the dotted line shown in the drawings connecting the code communication apparatus at the respective stations.

Relays CS and CSP are respectively normally energized and normally deenergized relays that are used in the initiation of a cycle of operation of the communication apparatus. Relay CSP is a back contact repeater of relay CS.

Relays CP and CPP are provided at the control office for causing the complete repeat of the stepping for an indication cycle, thus providing that there are 14 steps in an indication cycle as compared to 7 steps in a control cycle. These relays remain deenergized during a control cycle.

For the reception of controls at the field station, switch and signal application relays are used according to the usual practice, the magnetic stick relays 1WZ and 3WZ being provided for governing the power operation of the track switches of the crossovers 1 and 3 respectively, and signal control relays 2RGZ and 2LGZ, 4RGZ and 4LGZ, and 6RGZ and 6LGZ being provided for governing the signals 2, 4, and 6 respectively for both directions of traffic. These relays are all adapted in accordance with the usual practice to be positioned by momentary energization as an output of the code communication system connecting the control office and the field station, and are maintained in their last actuated positions by local stick circuits, or by magnetic stick characteristics, until such time as when a different control is transmitted from the control office for operation of such relays, or in the case of signal control relays, when the associated signal is accepted by a train, if stick signalling is provided as is assumed for this embodiment of the present invention.

Apparatus for the communication of indications from the field station to the control office is provided according to the usual practice, such apparatus including change relays CH at the field station for the initiation of the respective indication cycles of operation of the communication system, and circuit selections including code determining relays LC, governing the indication characters as selected marks or spaces for transmission.

Switch indication magnetic stick relays 1NWK, 1RWK, 3NWK, and 3RWK are provided at the control office in accordance with the usual practice for governing the energization of indicator lamps and the control panel 20 of the control machine. In addition to these relays being adapted for normal indication purposes, they have a second winding which is used for checking purposes as a part of the present invention in a manner to be more readily understood as the description progresses when reference is made to the mode of operation under specific assumed operating conditions.

Other relays including the track relays TR, track repeater relays TP, stop control relays B, and switch correspondence relays NCR and RCR are provided according to usual practice, and the control and functions of these relays are so well known in the art that it is considered unnecessary to give specific consideration as to this part of the system.

Having thus considered the organization in general of the apparatus of a specific embodiment of the present invention, a more detailed consideration will now be given as to the circuit organization upon considering certain typical modes of operation of the system.

Operation

Like most system organizations of this nature, the system is normally at rest in that it is inactive for the communication of control or indication codes until there is a new control designated for transmission, or until a new indication is required. Thus when all of the designated controls, and all of the new indications have been transmitted, normal conditions of the system are established, and it is these normal conditions that have been assumed in the drawings in indicating the positions of the respective

relays, it also being assumed that the track switches have last been operated to their normal positions, and that all of the signals are at stop, and that the track layout is unoccupied.

At this time, the change relays CH at the control office are all in their picked up positions and are maintained energized by stick circuits comparable to the stick circuit for the relay 1CH, extending from (+), including front contact 21 of relay 1CH, contact 22 of lever 1SML in its left-hand position, and upper winding of relay 1CH, to (-).

The normal switch indication relays 1NWK and 3NWK are shown as being picked up under conditions that are assumed as normal to correspond with the assumed normal positions of their associated track switches.

At the field station the magnetic stick switch control relays 1WZ and 3WZ (see Fig. 3) are illustrated as being in their picked up positions because it is assumed that the last control communicated from the control office has been for the power operation of the track switches of crossovers 1TS and 3TS to their normal positions. Thus the correspondence relays 1NCR and 3NCR are also energized to normal conditions to repeat the normal positions of the associated switches.

The field change relay CH is normally maintained picked up by a stick circuit provided according to usual practice so as to be interrupted when it is desired to initiate an indication cycle of operation of the code communication system in accordance with a change in a device to be indicated. For the purpose of an understanding of the present invention, it has been considered unnecessary to illustrate the communication of track occupancy indication and signal indications, and thus the portion of the stick circuit for the relay CH including selections by contacts of these devices is merely indicated by XX in the stick circuit. The organization of the stick circuit for the relay CH is such that the relay is maintained picked up under the conditions assumed to be normal by energy feeding through back contact 23 of relay 1RCR connected in multiple with front contact 24 of relay 1WZ, front contact 25 of relay 1NCR, front contact 26 of relay 3NCR, back contact 27 of relay 3RCR connected in multiple with front contact 28 of relay 3WZ, and front contact 29 of relay CH.

To consider a typical example of the mode of operation upon the establishment of a route, it will be assumed that, with the system in its normal condition as has been described, it is desired to set up a route for the passage of an eastbound train from signal 2 over the crossovers 3 and 1 respectively to the upper of the three tracks as illustrated in the track diagram on the control panel 20 (see Fig. 2). To designate the setting up of this route, the operator of the control machine actuates the switch control levers 3SML and 1SML to their respective reverse positions (right-hand operated positions), and then operates the signal control lever 2SGL to its right-hand position for designating the clearing of signal 2 for governing eastbound traffic. The actuation of these switch and signal control levers can be in the order in which they have been named, or all levers may be actuated at the same time, it being desirable for obvious reasons that the switch positions be designated before the designation of the signal to be cleared, or at least at the same time.

If it is assumed that the levers have all been actuated as described at substantially the same time, the relays 1CH, 3CH, and 2CH are all dropped away to initiate respective control cycles of operation of the code communication system for the communication of the designated switch and signal controls. The relay 1CH is dropped away because the shifting of the contact 22 of the lever 1SML to its right-hand position energizes the lower winding of relay 1CH and opens the circuit for the upper winding so that the flux is reversed in that relay, and thus the relay 1CH becomes dropped away and opens its own circuit at its front contact 21, which results in the

relay 1CH having both of its windings deenergized. By a similar circuit organization the relays 3CH and 2CH, which are associated with the signal control lever 2SGL, are dropped away. The relay 2CH is dropped away by the energization of its lower winding through the contact 30 of the signal control lever 2SGL when this lever is actuated from its center (stop) position to its right-hand position. It will be noted that a similar energization of relay 2CH would be effective if the lever 2SGL were operated to its left-hand position for designation of a signal to be cleared for westbound traffic.

A function of the designation of a new switch control by the actuation of a switch control lever is the knocking down of the switch indication relay for the opposite switch position, if such switch indication relay is picked up at that time. Thus, for example, upon actuation of the switch control lever 1SML to its right-hand position, the relay 1NWK is knocked down by the energization of a circuit including contact 52 of lever 1SML in its right-hand position, front contact 53 of relay 1NWK and lower winding of relay 1NWK. The energization of relay 1NWK with this polarity causes the knocking down of the relay, which opens the circuit which has just been energized at front contact 53.

Similarly when the lever 3SML is actuated to its right-hand position, the contact 54 of that lever, when closed in its right-hand position, applies energy through contact 55 of relay 3NWK to the lower winding of relay 3NWK so as to cause the armature of that relay to be knocked down.

Having thus called for new positions for the track switches of both crossovers 1TS and 3TS, the out-of-correspondence lamps 1CK and 3CK are respectively energized in accordance with the knocking down of the normal switch indication relays as has been described. Thus the lamp 1CK, for example, becomes energized through back contact 56 of relay 1RWK and back contact 57 of relay 1NWK.

In accordance with the relay 1CH being dropped away, a circuit is closed to cause the picking up of the relay 1LC extending from (+), including back contact 31 of relay LCS, front contact 32 of relay C, back contact 33 of relay 1CH, lower winding of relay 1LC, and back contacts 92 and 93 of relays 1RWK and 1NWK respectively, to (-). It will be noted that this circuit checks that the actuation of the switch control lever SML has been effective to knock down relay 1NWK. Thus no switch control can be transmitted until the corresponding switch indication relays NWK and RWK are dropped away.

Relay 1CH when picked up is maintained energized by a stick circuit including the winding of relay LCS. This circuit extends from (+), including back contacts 34, 35, and 36 of relays CPP, CP, and CSP, respectively, front contacts 37 and 38 of relays CS and L, respectively, winding of relay LCS, front contact 39 of relay 1LC, and upper winding of relay 1LC, to (-). Relay LCS when picked up closes a stick circuit through its front contact 40 to maintain the relays LCS and 1LC picked up throughout the transmission of a control code. Energy is applied to this stick circuit through any one of the stepping-relay contacts 41, 42, 43, or 44 of the relays IV, 2V, 3V, and 4V, or through the contact fingers 45 and 46 of the oscillator CT.

The picking up of the relay LCS initiates the operation of the oscillator CT, which in turn causes the stepping to be rendered effective, and the relay C is selectively energized or deenergized during the respective steps to cause the transmission of the selected code. The energization of the relay C is in accordance with the circuits selected through contacts of the relay 1LC, including front contacts 47, 48, and 49 for the respective steps in a manner well known to those familiar with the art, and as specifically shown and described in my above mentioned pending application. Each time that the relay C is energized during a particular step, it causes the transmission of

a mark by closing the line circuit through its front contact 50, and thus the selective opening and closing of the front contact 50 of relay C as the stepping progresses is effective to cause the transmission of a selected switch control code to cause the operation of the track switches of the crossover 1TS to their reverse positions in accordance with the designation of a reverse control code by the actuation of the switch control lever 1SML to its right-hand position.

It is to be understood that the switch control code transmitted from the control office to the field station includes code characters identifying the station with which the switch is associated, or, in other words, for this embodiment of the present invention, a separate station is assumed for each of the crossovers and for each pair of signals governing opposite directions of traffic. Thus each of the relays LC when picked up selects a distinctive station code for transmission, and renders the following characters of the code transmitted during that cycle as being selected by contacts (not shown) of the switch or signal control lever that is associated with that relay LC.

Having thus described the mode of operation for the transmission of a selected switch control code to the field station for the control of the track switches of crossover 1TS to their reverse positions, it is to be understood that a similar mode of operation is effective for the next cycle of operation for the transmission of a switch control code for the power operation of the track switches of the crossover 3TS to their reverse positions in accordance with the lever 3SML at the control office being operated to its right-hand position.

It will be obvious that the switch controls will be taken in the order that has been specified in accordance with the chain circuit organization for the energization of the relays LC, the closure of front contact 33 of the relay 1CH being essential to permit the picking up of the relay 3LC for the second control cycle. It will be noted that the relay 1CH is picked up during the first control cycle upon the energization of relay LCS by a circuit extending from (+), including front contact 51 of relay LCS, front contact 19 of relay 1LC, contact 22 of lever 1SML in its right-hand position, and lower winding of relay 1CH, to (-). The picking up of relay 1CH closes front contact 21 to establish a stick circuit effective to maintain the relay 1CH energized until the lever 1SML is actuated back to its normal position.

To consider now what happens with respect to the transmission of the signal control that has been designated, it will be noted that the picking up of the relay 3CH during transmission of the switch code for the crossover 3TS closes the front contact 53 in the chain circuit for the energization of relays LC so as to permit the feeding of energy at the end of the control cycle to the winding of the relay 2LC. The picking up of the relay 2LC, however, is made conditional, dependent upon the switch indication relays being positioned in accordance with an established route emanating from the signal that has been designated to be cleared. This is accomplished by a network of circuit selections in the circuits for the respective relays LC that are associated with the communication of signal controls which are so organized as to prevent the energization of any relay LC until a route is established as has been described. Thus the knocking down of the switch indication relays 1NWK and 3NWK upon designation of the crossovers 1TS and 3TS to be actuated to their reverse positions prevents the energization of a relay LC associated with the transmission of a signal control until an indication is received from the field that the switch controls that have been transmitted have been effective to cause the power operation of the associated track switches to their corresponding positions. Thus, although the relay 2CH is assumed to be in its dropped away position, the relay 2LC cannot be picked up until indications are received from the field that the track

switches have been operated in correspondence with the reverse positions that have been designated.

In accordance with the communication of the reverse control for the respective crossovers 1TS and 3TS, the relays 1WZ and 3WZ (see Fig. 3) are respectively actuated to their dropped away positions, and thus the control circuits governed by these relays become energized with reverse polarity to effect the power operation of the switch machines SM. Relay 1WZ, for example, is effective by the pole changing contacts 59 and 60 to cause the power operation of the track switches of the crossover 1TS to their reverse positions. By a similar mode of operation, the contacts 61 and 62 of relay 3WZ pole change the circuit for the switch machines SM associated with the power operation of the track switches of the crossover 3TS so as to effect their operation to their reverse positions.

It will be noted that the dropping away of the relay 1WZ opens the circuit for the normal correspondence relay 1NCR at front contact 63, and thus causes this relay to become dropped away. The dropping away of the relay 1NCR, however, does not cause the start of an indication cycle at this time by the shifting of its contact 25 because the back contact 24 of relay 1WZ has just been closed so as to maintain the relay CH energized during the crossover time of the contact 25. Similarly, the closure of back contact 28 of relay 3WZ just prior to the dropping away of the relay 3NCR prevents the opening of the stick circuit for relay CH upon the shifting of contact 26 of relay 3NCR.

When the track switches of the crossover 1TS have been operated to their reverse positions and locked, the reverse biased polar correspondence relay 1RCR is picked up through back contact 63 of relay 1WZ and pole changing contacts of the switch machine controlled mechanisms according to the usual practice. Similarly, when the track switches of the crossover 3TS are fully operated to their reverse positions and locked, energy of reverse polarity is applied through the circuit controllers of the associated switch machines to the wires 64 and 65 so that the biased polar relay 3RCR becomes picked up by energization through back contact 66 of relay 3WZ.

The shifting of the contact 23 upon the picking up of relay 1RCR opens the stick circuit for the indication start relay CH because the front contact 24 of relay 1WZ is open at this time, and thus an indication cycle is initiated. Similarly an indication cycle can be initiated in accordance with the shifting of the contact 27 of relay 3RCR upon the picking up of that relay, because the front contact 28 of relay 3WZ is open at that time. Thus an indication cycle is started, and indications as to the positions of the respective switch correspondence relays NCR and RCR of the respective crossovers are transmitted to the control office.

With the relay 1RCR in its picked up position during an indication cycle, energy is applied through front contact 67 of relay 1RCR, front contact 68 of relay LC, and wire 69 through the code communication system so as to apply energy to the wire 69a at the control office with a polarity to cause the picking up of the magnetic stick relay 1RWK. Similarly, with the relay 3RCR (see Fig. 3) picked up, energy is applied through front contact 70 of relay 3RCR, front contact 71 of relay LC and wire 72 to cause the energization through the code communication apparatus of the wire 72a (see Fig. 1) at the control office with a polarity to cause the picking up of the magnetic stick relay 3RWK by the energization of its upper winding. It will be noted that the picking up of the relays 1RWK and 3RWK causes the extinguishing of the out-of-correspondence lamps 1CK and 3CK by the opening of back contacts 56 and 73 respectively.

When the magnetic stick indication relays 1RWK and 3RWK have been picked up in accordance with indications received from the field station as has been described,

the circuit network for the energization of the relay 2LC is completed so that the signal control that is assumed to have been designated can now be transmitted. The relay 2LC, therefore, becomes picked up at this time by the energization of a circuit extending from (+), including back contact 31 of relay LCS, front contact 32 of relay C, front contact 33 of relay 1CH, front contact 58 of relay 3CH, front contact 74 of relay 6CH, front contact 75 of relay 4CH, back contact 76 of relay 2CH, lower winding of relay 2LC, contact 77 of the signal control lever 2SGL in its right-hand position, front contact 78 of relay 3RWK, back contact 79 of relay 3NWK, front contact 80 of relay 1RWK, and back contact 81 of relay 1NWK, to (—).

Thus the relay 2LC can be picked up, and the picking up of this relay establishes a stick circuit, including the winding of the relay LCS, and extending through the upper winding of relay 2LC and the stick contact 82 and the same circuit selections that have been described when considering specifically the stick circuit for the relay 1LC. The picking up of relay LCS initiates the stepping and thus a signal control code is transmitted over the line circuit to the field station having characters selected in accordance with the control of the relay C through contacts of the relay 2LC and of the signal control lever 2SGL in accordance with the usual practice for the transmission of signal control codes. Each character of the code is a mark or a space (if the code communication system according to my above mentioned co-pending application is used) in accordance with whether or not the front contact of the relay C is closed during the respective steps of the communication cycle. It will be noted from the circuit that has been described for the energization of the relay 2LC that this circuit required a front contact to be closed of either the normal or reverse indication relay for each crossover that is included in the respective routes emanating from the signal 2R. If the route were set up with the track switches of the crossover 3TS in their normal positions, it would only be required that the relay 3NWK be picked up to close front contact 83 because the crossover 1TS would not be involved in such a route. If, however, the route to be established were through the track switches of the crossover 3TS in their reverse positions and one track switch of crossover 1TS in its normal position, the circuit for the energization of the relay 2LC would necessarily require the closure of front contact 78 of relay 3RWK and the front contact 84 of relay 1NWK. It will therefore be readily apparent that by using a circuit network selected by contacts of the switch correspondence relays as has been described in the circuits for the relays LC for the respective signals, that it is arranged to automatically delay the transmission of a designated signal control until the prior designated switch controls have become effective to actuate the indication relays to positions in correspondence with the new positions to which the respective track switches have been operated.

The restoration at the end of the cycle of the relays LC which are provided for the transmission of signal controls, and the picking up of the associated relays CH, is comparable to the mode of operation that has been specifically described in accordance with the transmission of switch controls for the operation of the relays 1CH and 1LC.

It will be noted that the circuit for energization of the upper windings of the switch indication relays NWK and RWK at the control office check correspondence with the switch control levers for the associated track switches. That is, for example, the application of energy to the wire 69a by the code communication apparatus must energize the upper winding of relay 1RWK through contact 90 of lever 1SML in its right-hand position unless the relay 1RWK is already picked up. In this case the switch lever contact 90 is shunted out of the control circuit for the upper winding of relay 1RWK by

5
10
15
20

front contact 91 so that relay 1RWK can be knocked down by reverse polarity in its upper winding, irrespective of the position of the switch control lever SML. The circuit organization for the energization of the upper windings of the switch indication relays NWK and RWK is particularly to guard against the possibility of a switch indication relay being picked up to permit the transmission of a signal control under abnormal conditions where the transmission of an indication cycle from the field is initiated without the track switch being operated in response to the switch control that has been designated.

Having thus described one specific embodiment of a route check system as applied to a relatively simple track layout it is desired to be understood that the system is readily adaptable for use with practically any track layout to be encountered in practice, and it is to be further understood that various adaptations, alterations, and modifications may be applied to the specific form shown in accordance with the requirements of practice within the scope of the present invention as defined by the appended claims.

What I claim is:

1. A centralized traffic control system for railroads for the control of a plurality of track switches and signals at a field station by code communication from a distant control office comprising in combination, a normally-at-rest code communication system connecting the control office and the field station and effective when initiated at the control office to transmit selected control codes to the field station and effective when initiated at the field station to transmit selected indication codes to the control office, manually operable switch control designation means at the control office for designating respective switch control codes for transmission to the field station, said switch control designation means being effective when actuated to initiate said code communication system, normal and reverse magnetic stick indication relays at the control office for the respective normal and reverse positions of the respective track switches, circuit means for energizing each of said magnetic stick relays with one polarity in response to the designation by said manually operable means of the opposite position of the associated track switch or with the opposite polarity in response to the communication by said code communication system of the corresponding position of the associated track switch, and manually operable designation means at the control office for designating respective signal control codes for transmission to the field station, said signal designation means being effective when actuated to designate the clearing of a signal to initiate said code communication system, but not until one of said magnetic stick indication relays is actuated in correspondence with the full normal or full reverse position of its associated track switch for each track switch included in an available route emanating from the signal that has been designated.

2. A centralized traffic control system for railroads for the control of a plurality of track switches and signals at a field station by code communication from a distant control office comprising in combination, manually operable switch designation means at the control office for selectively designating normal and reverse switch controls desired for the respective track switches, manually operable signal designation means at the control office for selectively designating the clear and stop controls desired for the respective signals, a normally at rest code communication system effective when rendered active to communicate selected control codes from the control office to the field station, or to communicate selected indication codes from the field station to the control office, normal and reverse magnetic stick switch indication relays at the control office for the respective track switches, said switch indication relays being actuated in response to distinctive indication codes received from the field station, initiation means at the control office responsive to the actuation of

said manually operable means for initiating said code communication system into a cycle of operation for the communication of switch or signal control codes in accordance with whether said manually operable signal designation means has been actuated, circuit means effective in response to the designation of a switch control for transmission for actuating to a predetermined position the switch indication relay for the opposite switch position, and check circuit means requiring said switch indication relays to be conditioned in correspondence with switch positions for an established route emanating from a signal having a signal clearing code designated for transmission before such designation can become effective to initiate said code communication system into a cycle of operation for the transmission of a signal clearing coded to the associated signal.

3. A centralized traffic control system for railroads for the control of a plurality of track switches and signals at a field station by code communication from a distant control office comprising in combination, a normally at rest code communication system connecting the control office and the field station effective when initiated at the control office to transmit selected switch or signal control codes to the field station and effective when initiated at the field station to transmit selected indication codes to the control office, manually operable switch control designation means at the control office for designating respective switch control codes for transmission to the field station, said switch designation means being effective when actuated to initiate said code communication system, normal and reverse magnetic stick indication relays at the control office for the respective normal and reverse positions of the respective track switches, circuit means for energizing each of said magnetic stick relays with one polarity in response to the designation by said manually operable switch designation means of the opposite position of the associated track switch, said circuit means being effective to energize each of said magnetic stick relays with the opposite polarity in response to the communication of an indication by said code communication system of the corresponding position of the associated track switch, manually operable signal designation means at the control office for designating respective signal controls for each of the signals, a normally deenergized signal code determining relay effective when energized to initiate said code communication system for the transmission of a selected signal control code, and circuit means for energizing said signal control code determining relay for each signal when its associated signal is designated by said manually operable signal designation means as being controlled to a new position, said circuit means being effective only provided that there is one of said magnetic stick relays positioned in accordance with energization by said opposite polarity for each track switch in a route emanating from the signal having been designated.

4. A centralized traffic control system for railroads for the control of a plurality of track switches and signals at a field station remote from a control office comprising in combination, a normally at rest code communication system connecting the field station and the control office and effective when initiated at the control office to communicate designated switch and signal control codes to the field station, manually operable switch and signal control designation means at the control office operable respectively to a plurality of selected positions for each of the track switches and signals, a double-wound start relay at the control office for each track switch and for each signal, and circuit means for normally energizing one winding or the other of said start relay in accordance with the position of the associated manually operable means, said circuit means being effective upon the movement of the associated manually operable means to another position to shift energization of the associated start relay to the other winding with a change in the relative polarity, said circuit means being effective to normally maintain said

start relay energized through a front contact of the associated relay, whereby each start relay is dropped away upon a change in the position of the associated manually operable means, and the dropping away of the start relay opens its own circuit to remove energy from whichever winding has at last been energized.

5. A centralized traffic control system for the communication of controls for a signal from a control office to a field station comprising in combination, a manually operable three position selector device for the designation of the associated signals to be put to stop or cleared for one traffic direction or the other, a double-wound start relay at the control office for the three position selector device, circuit means for governing the energization of one winding or the other of said start relay selectively in accordance with the respective positions to which said device is actuated, said circuit means being effective to select the energization of the other winding of said start relay each time said three position device is actuated to a new position, and said circuit means being effective to energize each winding of said start relay always with the same polarity, but to oppositely polarize the two windings relatively, and said circuit means normally including a front contact of said start relay whereby the dropping away of that relay because of the reversal of polarity automatically opens the circuit for the last winding energized, and code communication apparatus including a line circuit connecting the control office and the field station effective in response to the dropping away of said start relay to communicate a selected signal control code to the field station in accordance with the position to which said manually operable three position device has been actuated.

6. A centralized traffic control system for the communication of controls for a track switch from a control office to a field station comprising in combination, a manually operable multiple position selector at the control office having respective normal and reverse positions for designation of respective normal and reverse switch controls to be communicated to the field station, a double wound start relay at the control office, circuit means for governing the energization of one winding or the other of said start relay selectively in accordance with the respective normal or reverse position to which said multiple position selector is actuated, said circuit means being effective to energize each winding always with the same polarity, but to oppositely polarize the two windings relatively, and code communication apparatus including a line circuit connecting the control office and the field station effective in response to the dropping away of said start relay to communicate a selected switch control code to the field station in accordance with the position to which said manually operable selector has been actuated.

7. A centralized traffic control system for the communication of controls for a track switch from a control office to a field station comprising in combination, a manually operable multiple position selector device at the control office having respective normal and reverse positions for designation of the respective normal and reverse switch controls to be communicated to the field station, a double wound start relay at the control office, circuit means for governing the energization of one winding or the other of said start relay selectively in accordance with the respective normal or reverse position to which said multiple position selector device is actuated, said circuit means being effective to energize each winding always with the same polarity, but to oppositely polarize the two windings relatively, said circuit means having energy normally fed for energization of the relay through a stick contact of said relay, and said circuit means having pickup energy momentarily applied after said start relay has initiated the transmission of a control code for the associated track switch, and code communication apparatus including a line circuit connecting

the control office and the field station effective in response to the dropping away of said start relay to communicate a selected switch control code to the field station in accordance with the position to which said manually operable means has been actuated.

8. A code communication system for the communication of selected controls for a multiple position device from a control office to a field station comprising in combination, a manually operable multiple position switch at the control office for designating the respective positions to which said device is to be controlled, a double wound start relay at the control office, circuit means for governing the energization of one winding or the other of said start relay selectively in accordance with the respective position to which said multiple position switch is actuated, said circuit means being effective to energize each winding always with the same polarity, but to oppositely polarize the two windings relatively, said circuit means having energy normally applied to one or the other of the selected windings of the relay through a front contact of said relay, and said circuit means having pickup energy momentarily applied after said start relay has initiated the transmission of a control code for the associated device, and normally at rest code communication apparatus connecting the control office and the field station effective in response to the dropping away of said start relay to communicate a selected control code to the field station for the operation of said device in accordance with the position to which said manually operable switch has been actuated.

9. A centralized traffic control system for the control of a plurality of track switches at a field station by code communication from a distant control office comprising in combination, normally at rest code communication apparatus including a line circuit connecting the control office and the field station and effective when initiated at the control office to transmit selected control codes to the field station and effective when initiated at the field station to transmit selected indication codes to the control office, manually operable switch control designation means at the control office for designating respective switch control codes for transmission to the field station, normal and reverse magnetic-stick indication relays at the control office for indicating the respective normal and reverse positions of the respective track switches, circuit means for energizing each of said magnetic-stick relays with one polarity in response to the designation by said manually operable means of the opposite position of the associated track switch and with the opposite polarity in response to the communication by said code communication system of an indication of the corresponding normal or reverse switch position for the associated track switch, initiating circuit means responsive to said manually operable switch designation for initiating said code communication apparatus into a cycle of operation for

5 10 15 20 25 30 35 40 45 50

the transmission of the designated switch control, said initiating circuit means being effective only provided that said normal and reverse magnetic-stick switch indication relays for the associated track switch are both actuated to the same position.

10. A centralized traffic control system for the control of a plurality of track switches and signals at a field station by code communication from a distant control office comprising in combination, normally at rest code communication apparatus connecting the control office and the field station and effective when initiated at the control office to transmit selected control codes to the field station and effective when initiated at the field station to transmit selected indication codes to the control office, manually operable switch control designation means at the control office for designating respective switch control codes for transmission to the field station, normal and reverse magnetic-stick indication relays at the control office for the respective normal and reverse positions of the respective track switches, circuit means for energizing each of said magnetic-stick relays with one polarity in response to the designation by said manually operable means of the opposite position of the associated track switch, said circuit means being effective to energize each of said magnetic-stick relays with the opposite polarity in response to the communication by said code communication system of the corresponding normal or reverse position of the associated track switch, initiating circuit means responsive to said 30 manually operable switch designation means for initiating said code communication apparatus into a cycle of operation for transmission of each designated switch control, said initiating circuit means being effective only provided that said normal and reverse magnetic-stick switch indication relays for the associated track switch are both actuated to the same positions, manually operable designation means at the control office for designating respective signal control codes for transmission to the field station, and initiating circuit means responsive to said manually operable signal designation means for initiating said code communication apparatus into a cycle of operation for the transmission of the designated signal control code, said initiating circuit means for the transmission of signal control codes being effective only provided that one of said magnetic-stick relays is actuated in correspondence with the full-normal or full-reverse position of its associated track switch for each track switch included in a route emanating from the signal that has been designated.
